UNITED STATES PATENT OFFICE.

RUSSELL C. JONES, OF BRONXVILLE, NEW YORK, ASSIGNOR TO THE GRISCOM
RUSSELL COMPANY, A CORPORATION OF DELAWARE.

OIL-COOLER.

1,355,980.

Specification of Letters Patent. Patented Oct. 19, 1920.

Application filed October 26, 1918. Serial No. 259,798.

To all whom it may concern:

Be it known that I, RUSSELL C. JONES, a citizen of the United States, residing at Bronxville, in the county of Westchester 5 and State of New York, have invented certain new and useful Improvements in Oil-Coolers; and I do hereby declare the following to be a full, clear, and exact description of the invention, such as will enable 10 others skilled in the art to which it appertains to make and use the same.

This invention relates to liquid cooling apparatus and has for its object to provide an apparatus for facilitating the exchange 15 of heat from one liquid in circulation to another, the invention being particularly applicable to the cooling of lubricating oil in circulation through engines or similar machinery.

It has heretofore been necessary to thoroughly agitate lubricating oil in its passage 20 through a cooling apparatus for the reason that the oil has a tendency to form a film on the cooled surfaces over which it is circulated, and as the film of oil is a poor conductor of heat it acts in effect to insulate 25 that part of the cooling surface on which the film forms, and virtually destroy its usefulness. If the oil is sufficiently agitated, 30 the film-forming tendency is materially lessened, and the most successful coolers heretofore have been those in which the water or other cooling liquid is circulated through the tubes of the cooler and oil is 35 circulated in the shell or other container where it is more or less agitated by passing over the tubes.

I have found, however, that superior cooling 40 effects may be had with coolers in which the oil or other liquid to be cooled is circulated through the tubes and the cooling liquid is circulated through the shell by using a novel tube design constructed to be self-cleaning, that is to say, so constructed that 45 the flow of the oil through the tube serves to clean off the oil as it attempts to thicken on the surface of the tube.

My improved tube construction is particularly advantageous when used in the U- 50 tube form of cooler in which the tubes are bent to U-shape and both ends of the tube supported in a single header in the cooler shell with the intermediate portion of the

tube unsupported. With my improved tube construction a much greater rigidity of the 55 tube in proportion to its length and weight is secured, so that interior supports for the curved ends of the tubes may be entirely dispensed with.

In my co-pending application, Ser. No. 60 259,797 filed concurrently herewith, I have described various modifications whereby the tubes are self-cleaning in the manner described, and any of the tube designs shown in that application may be employed in the 65 U-type construction, but the form of tube herein shown and described has peculiar advantages in the U-tube cooler and it is with such type of cooler that this application is concerned.

In said drawings, Figure 1 is a horizontal sectional view showing the arrangement of the tubes in the cooler; Fig. 2 is a cross section on line 2—2 of Fig. 1; Fig. 3 is a perspective view of one of the tubes; Fig. 4 is a vertical longitudinal section of a cooler having a modified form of tube; Fig. 5 is a perspective view of the tube employed in the cooler shown in Fig. 4; and Fig. 6 is a perspective view of a further modification 70 of the tube which may be employed with advantage in the cooler shown in Fig. 4.

Referring to the drawings, particularly 75 Figs. 1, 2 and 3, 1 indicates the shell of the cooler herein shown as of the ordinary substantially cylindrical construction open at each end and provided with inlet and outlet passages 2 and 3 for the heat-absorbing fluid. The fluid used to absorb the heat 80 from the oil is usually water and it will be understood that water in sufficient quantity will be freely circulated through the shell, entering the inlet passage 2, passing around the interior middle baffle 4 and thence through the exit passage 3 by means of a 85 suitable circulating pump or other apparatus, not shown.

The tubes 5 are wholly supported in a header or tube plate 6, the tube being expanded or otherwise secured in the tube 100 plate 6 in any approved manner. The tube plate 6 is attached to the end of the shell by means of a feed drum 8 which is clamped to the back of the plate by suitable bolts 9. The feed drum is divided into two compartments 105 7 and 11, respectively, by means of a

middle web or diaphragm 10 which is clamped against the tube plate by the bolts 9.

Each of the tubes 5 is bent to U-shape 5 and is arranged in the shell with one leg at one side of the baffle plate 4 and the other leg at the other side in the usual manner, so that one end of each of the tubes is connected to the compartment 7 of the feed 10 drum while the other ends of the tubes are connected to the compartment 11, the preferred arrangement being such that the cooling liquid flows in the opposite direction to the liquid being cooled, after the 15 manner of a counter-current heater.

The tubes employed in my improved cooler are not round, as heretofore employed, but are flattened and may be formed by taking an ordinary round tube and running it 20 through rollers so as to flatten it through its entire length except at its ends to approximately the cross section shown in Fig. 2, the ends of the tubes being left round so that they may be attached to the tube plate 25 by the ordinary methods now in use.

It will be understood that in the cooler shown in Figs. 1 and 2, the baffle plate 4 is arranged vertically in the shell instead of horizontally and that the tubes are curved 30 with one flat face on the inside of the bend, in which direction the tubes can be bent much more readily than round tubes, and with much less stress of the metal as will be obvious. The two legs of the tube are attached to the tube plate 6 in a substantially 35 horizontal plane so that the long diameter of the tube cross section extends vertically, or, in other words, the tubes are arranged edgewise in the shell, in which position they 40 are much more rigid than ordinary round tubes and have much greater strength to resist sagging at the unsupported intermediate portions. By this arrangement tubes much longer in proportion to their cross 45 sectional area than heretofore employed may be safely used, thereby giving a longer path to the oil with a consequent greater degree of cooling for the same temperature difference and rate of flow.

50 In Fig. 4 I have shown a modification of the cooler in which the tube shown in Fig. 5 is employed. As here shown, the tubes 5^a have the flat faces of their two legs in the same plane and are arranged in the shell 55 with one leg vertically over the other. In this form of the cooler the shell is divided into two compartments by a horizontal baffle, as indicated in Fig. 2, so that all the tubes have one end attached to the tube plate 60 at one side of the baffle and their other ends all attached to the tube plate at the other side.

The tube of this design forms an exceedingly rigid structure and is particularly 65 advantageous where extra long tubes are to

be used. The tube may be formed advantageously by first bending the round tube to U-shape and then flattening all of the tube except the short lengths at the ends which are inserted in the tube plate.

The tube 5^b shown in Fig. 6 is closely similar to the tube 5^a and is to be arranged in the same way in the shell. This tube has its straight portions flattened in the same manner as the legs of tube 5^a but the intermediate curved portion is left round. These tubes may be conveniently made by flattening a round tube at two different points in its length and then bending the tube at the intermediate portion which is left round.

By flattening the tube in the manner described the cross sectional area of the tube is reduced, thereby increasing the velocity of the oil in passing through the tube so that the moving oil stream scours the surface of the tube, removing any oil tending to congeal and adhere thereto. Any appreciable congealing of the oil on the surface of the tube will, due to the short distance between the opposite walls of the tube, tend to obstruct the tube, so that the force of the moving stream through the tube will wash the film away. A film of congealed oil of the same thickness on a round tube would have little effect on the bore of the tube and would not be washed off unless the velocity of the oil was so high as to be but little cooled in its passage through the same length of tube.

Also, with the fluid in a thin stream, the entire volume of oil is in close proximity to the surface of the tube during its passage through the cooler, thereby effecting a more uniform and rapid cooling of the oil.

It will of course be understood that the shell construction selected for illustration is by way of example only and that the invention is not to be considered limited in any sense thereto.

It will also be understood that the tube construction and its arrangement within the shell may be varied without departing from the spirit of the invention as defined in the appended claims.

I claim:

1. In an apparatus for effecting the exchange of heat from one fluid to another, the combination of a shell or vessel for one of the fluids, tubes for the other fluid, said tubes being flattened to bring the opposite walls close together to form the circulating fluid into a thin stream with all parts in close proximity to the tube walls, said tubes being of U-shape and arranged with the long axis of their cross section in a vertical plane.

2. In an apparatus for effecting the exchange of heat from one fluid to another, the combination of a shell or vessel for one of the fluids, tubes for the other fluid, said tubes being flattened throughout the major por-

tion of their length to bring the opposite walls close together to form the circulating fluid into a thin stream with all parts in close proximity to the tube walls, said tubes being of U-shape with the flat faces of their two straight portions in the same plane and supported in the shell with the two legs of the U in substantially the same vertical plane.

10 3. In an apparatus for effecting the exchange of heat from one fluid to another, the combination of a shell or vessel for one of the fluids, tubes for the other fluid, said tubes having end portions of circular cross sec-

tion, an intermediate portion of a perimeter 15 substantially equal to the circumference of the end portions but flattened to bring the opposite walls close together to form the circulating fluid into a thin stream with all parts in close proximity to the tube walls, 20 said tubes being of U-shape with the flat faces of their two straight portions in the same plane and supported in the shell with the two legs of the U in substantially the same vertical plane.

25 In testimony whereof I affix my signature.

RUSSELL C. JONES.
